UNITED STATES PATENT OFFICE.

MORRIS R. MOFFITT, OF PECK, KANSAS.

PENCIL CALENDAR AND CLIP.

985,051.

Specification of Letters Patent. Patented Feb. 21, 1911.

Application filed March 17, 1910. Serial No. 549,860.

To all whom it may concern:

Be it known that I, MORRIS R. MOFFITT, a citizen of the United States, residing at Peck, in the county of Sumner, State of 5 Kansas, have invented certain new and useful Improvements in Pencil Calendars and Clips; and I do hereby declare the following to be a full, clear, and exact description of the invention, such as will enable others 10 skilled in the art to which it appertains to make and use the same.

The invention relates to a calendar and clip and more particularly to the class of 15 calendars and clips therefor for use on pencils, pens or other writing instruments.

The primary object of the invention is the provision of a device of this character in which calendar leaves may be interchangeably mounted upon a pencil, pen or the like 20 so that the said calendar may be readily visible to the writer.

Another object of the invention is the provision of a device of this character in which separable sheets having indicia on 25 both sides of each sheet whereby the calendar months may be carried by a pen or pencil in a convenient manner so as to be exposed or made visible to the user of the pen or pencil.

A further object of the invention is the provision of a device of this character in which a clip is so arranged as to be conveniently carried upon a pen or pencil, so that a plurality of sheets containing the 35 calendar months may be carried by the pencil, whereby they will be handy and readily visible by the user of the pen or pencil.

A still further object of the invention is the provision of a device of this character 40 which may be readily and quickly applied to various styles of pencils or pens for convenient use by the user thereof, the device being simple in construction and inexpensive in the manufacture.

In the drawings accompanying and forming part of this specification is illustrated the preferred form of embodiment of the invention which to enable those skilled in the art to carry the invention into practice, 45 will be set forth at length in the following description, while the novelty of the invention will be pointed out in the claims succeeding the description.

It is to be understood of course that 50 changes, variations and modifications may be made to the device such as come properly

within the scope of the appended claims without departing from the spirit of the invention or sacrificing any of its advantages.

In the drawings:—Figure 1 is a fragmentary top elevation of a pencil with the invention applied thereto. Fig. 2 is a similar view with the clip shown in an open position. Fig. 3 is an enlarged end elevation of 65 a pencil with the invention applied thereto. Fig. 4 is a perspective view of the device removed from the pencil. Fig. 5 is a plan view of one of the sheets of the calendar pad. Fig. 6 is a side elevation of a pencil 70 with the invention thereon, the same being in opened position.

Similar reference characters indicate corresponding parts throughout the several views in the drawings.

Referring to the drawings by numerals 5 designates a lead pencil which is of the ordinary well-known construction having the usual ferrule 6 at one end thereof in the socket of which is mounted an erasive rubber 7 although it is to be understood that in lieu of the lead pencil there may be substituted a pen holder or other writing instrument, the pencil being shown merely for the sake of illustrating the construction and manner of mounting the calendar device as will be hereinafter more fully described.

The calendar device comprising a split wire ring member 8 having its end portions bent to form alining eye loops 9 and offset gripping spurs or fingers 10, the ring member 8 being encircled about the ferrule 6 at one end of the pencil 5 whereby the said member may be readily detached at will from the pencil.

Hinged to the eye loops 9 is a clipping jaw comprising a single strand of rigid wire preferably steel wire bent to form spaced parallel side portions 11 united at one end by an arcuate shaped end yoke portion 12, the side portions at their opposite extremities being bent upwardly at right angles thereto and then outwardly as at 13, one outwardly bent portion being inturned at 14 and engaged with the other end 100 portion by means of linked eyes 15, the said inturned portion 14 being passed through the eye loops 9 of the ring member and forms the pivotal connection for the clipping jaw of the device. This jaw when 105 in closed position frictionally embraces substantially one half of the diameter of the

body of the pencil whereby a calendar pad may be securely held thereon in a manner as will be hereinafter more fully described.

The calendar pad comprises a plurality 5 of sheets 16 preferably formed from paper although the same may be constructed from any other suitable material and these sheets each is printed on both of its faces with indicia of the months, days of the week and 10 days of the month to provide a calendar so that the aggregate number of sheets will contain at least 18 consecutive calendar months although the calendar period may be varied as required to suit the purposes of 15 the user of the device. The said sheets are placed one upon the other so that the under sheet will lie against the body of the pencil 5 and on closing the hinged jaw it will securely fasten the said sheets in proper position on the pencil and at the same time will effect the penetration of the gripping fingers 10 into the number of sheets so as to prevent the latter from becoming longitudinally displaced or otherwise disarranged with respect to each other relative 25 to their normal arrangement when secured to and carried by the said pencil.

Whenever it is desired to turn anyone of the sheets or to dismount the same for any 30 purpose it can be so turned by raising the jaw and lifting the outmost sheet whereby it will be readily removed from the gripping

fingers thus freeing the same for the desired purpose.

What is claimed is;—

1. In a pencil device, a jaw adapted to grip the pencil to hold a plurality of calendar sheets on the same, and a clip for pivotally holding the jaw on said pencil, said clip having means for holding calendar 40 sheets on the pencil.

2. In a pencil device, a jaw adapted to grip the pencil to hold a plurality of calendar sheets on the same, said jaw lying parallel with said pencil, and a clip for pivotally holding the jaw to said pencil, said clip having fingers for penetrating the sheets of said calendar.

3. In a pencil device, a jaw adapted to grip the pencil to hold a plurality of calendar sheets on the same, said jaw comprising portions adapted to lie parallel with said pencil, and a pintle portion, and a clip hinged to the pintle portion for securing the jaw to said pencil, said clip being formed 55 with gripping fingers for holding the sheets of a calendar.

In testimony whereof, I affix my signature, in presence of two witnesses.

MORRIS R. MOFFITT.
